Des. 236,752
Patented Sept. 9, 1975

236,752

CYLINDRICAL STAMP

Takaji Funahashi, 1, 2-chome, Kitatakasho-machi,
Nishi-ku, Nagoya-shi, Aichi-ken, Japan

Filed Nov. 9, 1973, Ser. No. 414,433

Term of patent 14 years

Int. Cl. D19—02

U.S. Cl. D64—10

FIG. 1

FIG. 2

FIG. 3

FIG. 4

FIG. 5

FIG. 7

FIG. 6

FIG. 8

FIG. 9

FIG. 1 is a perspective view of a cylindrical stamp showing my new design in closed condition;

FIG. 2 is another perspective view of the stamp with a cap on the other end thereof;

FIG. 3 is a rear elevational view of the stamp in FIG. 1;

FIG. 4 is an exploded side elevational view thereof;

FIG. 5 is a top plan view of the stamp in FIG. 1;

FIG. 6 is a bottom plan view of the stamp in FIG. 1;

FIG. 7 is a top plan view of the body of the stamp in FIG. 2;

FIG. 8 is a bottom plan view of the cap of the stamp; and

FIG. 9 is a front elevational view of the stamp in FIG. 2.

I claim:

The ornamental design for a cylindrical stamp, as shown.
